UNITED STATES PATENT OFFICE.

WILLIAM J. SCHOONOVER, OF BELVIDERE, ILLINOIS.

GEARING FOR WASHING-MACHINES.

1,274,088.

Specification of Letters Patent. Patented July 30, 1918.

Application filed September 15, 1917. Serial No. 191,508.

To all whom it may concern:

Be it known that I, WILLIAM J. SCHOONOVER, a citizen of the United States, and a resident of Belvidere, in the county of

Boone and State of Illinois, have invented certain new and useful Improvements in Gearing for Washing-Machines, of which the following is a full, clear, and exact specification.

10 My invention is concerned with gearing for washing machines of the high-speed fly-wheel, lever-actuated pounder type, and is designed to produce a gearing of the class described that shall be extremely simple in 15 its construction and withal effective in its operation. It is further concerned with a simple combination whereby the pounder shaft may also be rotated through a few degrees during its movement in one direction, 20 but not in the other.

To illustrate my invention, I annex here-to two sheets of drawings, in which the same reference characters are used to designate identical parts in all the figures, of which—

25 Figure 1 is a central vertical section through the machine;

Fig. 2 is a top plan view in section on the line 2—2 of Fig. 1;

30 Fig. 3 is a detail, on an enlarged scale, in central vertical section, through the cover of the tub;

Fig. 4 is an inverted plan view as seen on the line 4—4 of Fig. 3;

35 Fig. 5 is a plan view as seen in section on the line 5—5 of Fig. 3;

Fig. 6 is a detail in section, as seen on the line 6—6 of Fig. 2; and

Fig. 7 is a detail as seen from line 7—7 of Fig. 1.

40 In carrying out my invention, the gearing is ordinarily applied to the tub 10, of the customary construction, supported on the legs 11 and provided with the cover 12, which is connected to the top by the hinges 45 13, which are of a peculiar design and construction, as will be hereinafter explained.

Secured on the cover is the casting 14 which furnishes the framework for the gearing, and at one end thereof is the pair of 50 downturned ears 15, forming a part of the aforesaid hinge 13, in which, upon the pin 16, is fulcrumed the hand lever, which preferably takes the form of the pair of bars 17, pivoted as above described, and having 55 the customary wooden handle 18 secured be-

tween their upper ends. At the inner end of the casting 14 is formed the cup 19, which is seated in the center of the cover, and has extending downward from its center the cylindrical bearing sleeve 20, through which reciprocates the pounder shaft 21, which has the customary spider 22 secured at its lower end, this spider having the inverted cups 23 secured thereon, one at the outer end of each radial arm. The pounder shaft 21 is secured, 60 so that it can rotate therein, in the bearing sleeve 24, which projects outwardly from the center of the yoke or cross-head 25, a convenient method of securing the shaft in place being that shown in Fig. 1, where it 65 will be seen that a pair of collars 26 and 27 are pinned to the shaft 21 directly above and below the sleeve 24. As a further guide for the vertically reciprocating shaft 21, I 70 preferably provide the bearing 28, which cooperates with the upper end of the shaft 21 and is preferably formed at the uppermost portion of the gear casing 29, which is supported at the upper end of the bracket 30 secured to or near the inner end of the casting 14. Projecting inwardly from the bearing sleeve 21 formed at the center of the gear casing 29, and connected to the bracket 30 by the rib 32, is the bearing stud 33, on 75 which is journaled the spur gear wheel 34, 80 which has the eccentric bearing pin 35 projecting outwardly therefrom into the horizontal channel 36 formed in the rear face of the yoke or cross-head 25, and preferably provided with a rectangular bearing block 85 37 journaled thereon and co-operating with the channel 36. Between the block 37 and the gear wheel 34 on the pin 35 is pivoted 90 the inner end of the pitman 38, the outer end of which is pivoted on the pin 39 secured 95 between the bars 17. Journaled in the bearing sleeve 40, which is formed at the end of the rib 32, is a horizontal shaft 41, which has on its inner end the spur gear pinion 42 meshing with the spur gear wheel 34, and 100 on its outer end is secured the hub of the heavy fly-wheel 43. To prevent the cross-head 25 from swinging about the shaft 21 as a center, I secure on it a small plate 44 spaced away from the cross-head to form 105 an open slot which slides up and down on the vertical rod 45 secured to and projecting upward from the casting 14.

With the construction shown and described, it will be obvious that as the hand 110

lever 18 is operated, the spur gear wheel will be rotated at a speed corresponding to the speed at which the handle is operated, and in its rotation will raise and lower the 5 pounder shaft, with the attached cups 23 in the tub, and at the same time the fly-wheel 43 will be speeded up so that its momentum will assist in the operation of the machine.

While the construction thus far described 10 would reciprocate the pounder shaft 21 vertically, it is desirable to have the same rotate through a few degrees at each downward movement, and for this purpose I employ the mechanism best illustrated in Figs. 15 3, 4 and 5, where it will be seen that the cup 19 is provided with the cover plate 46 secured thereto in any suitable manner, as by the screws 47. The under surface of this 20 cover plate 46, which is provided with a central aperture through which the shaft 21 reciprocates, is provided with one or more radial teeth or lugs 48, which preferably have one of their sides vertical, while the other sides are inclined in the manner of an 25 ordinary saw-tooth. Pressed against these teeth 48 are the teeth 49 of a ratchet disk 50, which is splined on the shaft 21 by the spline tooth 51 formed or secured in the edge of the central aperture thereof, and 30 entering the helical groove 52 formed in the shaft 21. It will of course be understood that this groove can be given any desired shape to produce any desired number of degrees of rotation at any desired part of the 35 downward movement, say, of the shaft 21. A helically coiled expanding spring 53 interposed between the bottom of the cup 19 and the under side of the ratchet disk 50 holds the latter yieldingly in engagement with the 40 teeth 48, and it will of course be understood that the teeth 48 are complementary of the teeth 49, so that the disk 50 is free to turn in one direction under the action of the spline groove as the shaft 21 rises without 45 rotation, the friction between the sleeve 20 and the bearing 28 and the shaft 21, augmented by the resistance to rising offered by the cups 23, being sufficient to overcome the slight friction between the two sets of teeth. 50 When, however, the sleeve 24 is forced down, the coöperation of the vertical faces of the two sets of teeth prevents the ratchet disk 50 from rotating in the other direction, and the disk not yielding, the spline groove 52 compels the shaft 21 to rotate through the angular distance for which the groove 52 is 55 designed.

The other member of the hinge is best 60 shown in Fig. 7, where it will be seen to consist of a casting 53^a screwed or otherwise secured to the side of the tub well below the top, and provided with the pair of ears 54 coöperating with the ears 15 and the fulcrum pin 16. This construction and location 65 of the hinge lowers the fulcrum of the

lid 12 so that the large, eccentrically-located cups 23 can be freely swung out of the top, which would not be possible with the same sized cups in the same eccentric location if the hinge were above or on a line with the 70 top of the cover, as has been the practice heretofore.

To assist in opening the lid, I counterbalance it by employing the helically-coiled contractile spring 55 secured at one end to 75 the side of the tub, as by the hook 56 formed on the downward extension 57 of the casting 53^a. The other end is hooked over the arm 58, which is secured to the casting 14, in any desired manner, projecting rearwardly between the bars 17 of the handle, as clearly shown in Fig. 1.

While I have shown and described my invention as embodied in the form which I at present consider best adapted to carry 85 out its purposes, it will be understood that it is capable of modifications, and that I do not desire to be limited in the interpretation of the following claims except as may be necessitated by the state of the prior art. For 90 instance, I might make the frame of two or more castings, instead of a single one.

What I claim as new, and desire to secure by Letters Patent of the United States, is:

1. In a gearing, the combination with a 95 support having bearing ears at one end thereof, of a hand lever of the second class fulcrumed between said ears, a bearing for a reciprocating rod in the other end of the support, a rod in said bearing, a cross-head 100 carried by said rod, a gear wheel journaled on an axle carried by the support in the plane in which the rod reciprocates, an eccentric bearing pin projecting from the wheel into the cross-head, and a pitman connecting the hand lever and the eccentric bearing-pin. 105

2. In a gearing, the combination with a support having bearing ears at one end thereof, of a hand lever of the second class fulcrumed 110 between said ears, a bearing for a reciprocating rod in the other end of the support, a rod in said bearing, a cross-head carried by said rod, a gear wheel journaled on an axle carried by the support in the plane in which the rod reciprocates, an eccentric bearing-pin projecting from the wheel into the cross-head, a pitman connecting the hand lever and the eccentric bearing-pin, a fly wheel 115 also journaled on the support, and a pinion rigidly connected to the fly-wheel meshing with the gear wheel. 120

3. In a gearing, the combination with a support, of a shaft reciprocating to and fro in said support having a helical spline 125 groove therein, a ratchet disk mounted in the support and through which the shaft reciprocates having a spline lug entering the groove, a detent lug on the support coöperating with the ratchet disk to prevent its 130

- rotation in one direction, and means for holding the ratchet disk yieldingly in engagement with the lug. 5
4. In a gearing, the combination with a support, of a shaft reciprocating to and fro in said support having a helical spline groove therein, a ratchet disk mounted in the support and through which the shaft reciprocates having a spline lug entering the groove, a detent lug on the support coöperating with the ratchet disk to prevent its rotation in one direction, and a helically-coiled expanding spring interposed between the support and the ratchet disk to hold the latter yieldingly in engagement with the detent lug. 10
5. In a gearing, the combination with a frame having bearing ears at one end thereof, of a hand lever of the second class fulcrumed between said ears, a bearing for a reciprocating rod in the other end of the frame, said bearing being associated with a cup recess, a rod having a helical spline groove therein mounted to reciprocate in said bearing, a cross-head in which the rod is mounted to rotate, a gear wheel journaled on an axis carried by the frame in the plane in which the rod reciprocates, an eccentric bearing-pin projecting from the wheel into the cross-head, a pitman connecting the hand lever and the eccentric bearing-pin, a cover for the cup recess having a radial detent lug on its under surface, a ratchet disk mounted in the cup and having ratchet teeth coöperating with the detent lug, and having a spline lug coöperating with the groove in the rod, and a helically-coiled expanding spring interposed between the bottom of the cup and the adjacent side of the 15 ratchet disk. 20
6. In a gearing, the combination with a support having bearing ears at one end thereof, of a hand lever of the second class fulcrumed between said ears, a bearing for a reciprocating rod in the other end of the support, a rod in said bearing, a cross-head carried by said rod, a gear wheel journaled on an axle carried by the support in the plane in which the rod reciprocates, an eccentric bearing-pin projecting from the wheel into the cross-head, a pitman connecting the hand lever and the eccentric bearing-pin, and means for preventing the rotation of the cross-head. 25
7. In a washing machine, the combination with a tub, of a hinged cover therefor, operating mechanism on said cover, and a counterbalance spring interposed between said cover and tub. 30
8. In a washing machine, the combination with a tub, of a cover therefor, operating mechanism on said cover depending into the tub, and a hinge secured to said tub and cover with its pivot below the top of the tub, for the purpose described. 35
9. In a washing machine, the combination with a tub, of a cover therefor, operating mechanism on said cover depending into the tub, the casting on the lid having a pair of ears overhanging the edge and extending below the top of the tub, and a hinge member coöperating therewith having coöperating ears also below the top of the tub secured to the side thereof. 40
10. In a washing machine, the combination with a tub, of a cover therefor, operating mechanism on said cover depending into the tub, the casting on the lid having a pair of ears overhanging the edge and extending below the top of the tub, a hinge member coöperating therewith having coöperating ears also below the top of the tub secured to the side thereof, and an operating lever for said mechanism pivoted on the hinge pin between the two pairs of ears. 45
11. In a washing machine, the combination with a tub, of a cover therefor, operating mechanism on said cover depending into the tub, the casting on the lid having a pair of ears overhanging the edge and extending below the top of the tub, a hinge member coöperating therewith having coöperating ears also below the top of the tub secured to the side thereof, an operating lever for said mechanism pivoted on the hinge pin between the two pairs of ears, and having a slot therethrough in the plane of the top of the lid, an arm projecting rearwardly from the top of the cover through said slot, a hook extending outwardly from the hinge member, and a helically-coiled contractile spring connecting the arm and the hook. 50

In witness whereof, I have hereunto set my hand and affixed my seal, this 11th day of September, A. D. 1917.

WILLIAM J. SCHOOENOEVER. [L. S.]

Witness:

JOHN HOWARD McELROY.
